YARN GUARD FOR STOP MOTION

Morris Saslowsky, East Meadow, N.Y., assignor to Wesco Industries Corporation, Plainview, N.Y.

Filed Apr. 12, 1974, Ser. No. 460,475

Term of patent 14 years

Int. Cl. D15—6

U.S. Cl. D47—5

FIG. 1.

FIG. 2.

FIG. 3.

FIG. 4.

FIG. 5.

FIG. 6.

FIG. 7.

FIG. 1 is a perspective view of a yarn guard for stop motion showing my new design;

FIG. 2 is a left side elevational view thereof;

FIG. 3 is a front elevational view thereof;

FIG. 4 is a right side elevational view thereof;

FIG. 5 is a top plan view thereof;

FIG. 6 is a rear elevational view thereof; and

FIG. 7 is a bottom plan view thereof.

I claim:

The ornamental design for a yarn guard for stop motion, substantially as shown.
